UNITED STATES PATENT OFFICE.

AUGUST JOHN STENCELL, OF PEMBROKE, ONTARIO, CANADA.

STOVE-POLISH.

1,382,026.

Specification of Letters Patent. Patented June 21, 1921.

No Drawing.

Application filed October 10, 1919. Serial No. 329,850.

To all whom it may concern:

Be it known that I, AUGUST JOHN STENCELL, a subject of the King of Great Britain, and resident of the town of Pembroke, in the Province of Ontario, Dominion of Canada, have invented certain new and useful Improvements in Stove-Polish, of which the following is a specification.

This invention relates to improvements in stove polish, and the objects of the invention are to permit of the polish being applied to a heated stove without any disagreeable results arising therefrom, such as smoke or smell, or collection of dust, to render the polish capable of being applied to nickel and the bright portions of a stove with an effect equal to that which it has on the body portion, so that both the blackened portion and the polished portions of the stove can thus be simultaneously attended to and thus result in a saving of time and labor.

For a complete understanding of my invention attention is particularly directed to the following specification.

In manufacturing this polish I have found that the following proportions of the ingredients give good results:

30 Lubricating graphite 2 lbs.
Shoe polish 2 lbs.
Oil of sassafras $\frac{1}{8}$ oz.

These ingredients are mixed together and

form a pasty mass which is of a dull grayish black in color, and the polish can be applied to a stove by means of a brush even when the stove is hot and the stove may be subsequently polished and brightened by rubbing with a dry brush. In polishing bright or nickel ware the polish is applied with a soft cloth and after it has dried it is then rubbed off with the same cloth which should then be dried and used as a polishing rag.

I have found that this polish gives excellent results in practice and does not collect dust and neither dries, smokes nor smells.

It may be stated that no invention is claimed for the ingredients referred to as shoe polish. Any well known polish can be used.

What I claim as my invention is:

A stove polish of the character described, comprising a pasty mass having the following ingredients in the proportions stated: 55

Lubricating graphite 2 lbs.
Shoe polish 2 lbs.
Oil of sassafras $\frac{1}{8}$ oz.

In witness whereof I have hereunto set 60 my hand in the presence of two witnesses.

AUGUST JOHN STENCELL.

Witnesses:

MARGARET RONEY,
ALBERT BOYCE.
